DESIGN FOR A TRAY

John S. Connors, Cleveland, Ohio

Application December 19, 1946, Serial No. 135,603

Term of patent 3½ years

(Cl. D44—10)

To all whom it may concern:

Be it known that I, John S. Connors, a citizen of the United States, residing at Cleveland, in the county of Cuyahoga and State of Ohio, have invented a new, original, and ornamental Design for Trays, of which the following is a specification, reference being had to the accompanying drawing, forming part thereof, in which:

Fig. 1 is a bottom perspective view of a tray, showing my new design, and

Fig. 2 is a top perspective view thereof.

I claim:

The ornamental design for a tray, as shown.

JOHN S. CONNORS.
